(57) **CLAIM**

The ornamental design for a holder device, as shown and described.

DESCRIPTION

FIG. 1 is a right perspective view showing an embodiment of the holder device;

FIG. 2 is a front view thereof;

FIG. 3 is a back view thereof;

FIG. 4 is a right-side view thereof;

FIG. 5 is a left-side view thereof;

FIG. 6 is a top plan view thereof;

FIG. 7 is a bottom plan view thereof;

FIG. 8 is a right perspective view thereof that additionally shows the holder device holding an object;

FIG. 9 is a right perspective view showing another embodiment of the holder device;

FIG. 10 is a front view thereof;

FIG. 11 is a back view thereof;

FIG. 12 is a right-side view thereof;

FIG. 13 is a left-side view thereof;

FIG. 14 is a top plan view thereof;

FIG. 15 is a bottom plan view thereof; and,

FIG. 16 is a right perspective view thereof that additionally shows the holder device holding an object.

The dash-dot-dash broken lines in FIGS. 9-16 represent a boundary and form no part of the claimed design. The remaining broken lines in FIGS. 8-16 depict environment and form no part of the claimed design. Any surface shading forms no part of the claimed design and is utilized to illustrate the surface contours of the holder device.
